WATER-HEATING APPARATUS.

1,078,623.

Specification of Letters Patent.

Patented Nov. 18, 1913.

Application filed October 15, 1909. Serial No. 522,742.

To all whom it may concern:

- Be it known that we, JOHN C. JONES, JOSEPH W. GAMBLE, and HORACE E. SIBSON, citizens of the United States, residing at 5 Philadelphia, in the county of Philadelphia and State of Pennsylvania, have invented certain new and useful Improvements in Water-Heating Apparatus, of which the following is a specification.
- 10 This invention relates to water heating apparatus and has reference particularly to apparatus for heating water which is to be used in the boilers of locomotives or other steam engines or in heating systems.
- 15 The invention is directed to the provision of an improved form of water heating apparatus which is reliable and efficient in operation, which may be constructed at comparatively low cost and with which economy 20 of operation is obtained by reason of the utilization of the heat contained in steam exhausted or blown off from boilers for heating water which is afterward to be used in boilers or heating systems.
- 25 The apparatus constructed in accordance with our invention is of particular utility in locomotive round-houses for heating water to be used in washing and filling locomotive boilers, the steam blown off from the boilers 30 being employed for heating this washing and boiler-feed water.

In accordance with the invention a tank is provided for the storage of water which is to be fed to the boilers and means are provided for passing steam exhausted or blown off from a boiler through the water in the tank so as to raise the temperature of this water; and in combination with these parts, a heater is employed into which cold water 35 is admitted and wherein this cold water is subjected to the heating effect of steam so as to raise the temperature of the water, after which this heated water is admitted to the storage tank. In order to utilize the heating 40 effect of the steam in the heater to the full extent a circulating system is provided by which is maintained a continuous circulation of the water in the storage tank through the heater and back to the storage tank. This 45 circulating system maintains a stream of water from the storage tank passing through

the heater at all times so as to take up the heat units in the steam passing through the heater, and if water is drawn from the storage tank so as to reduce the level of the 55 water stored therein, connections are automatically opened for introducing additional water from a cold water supply pipe to the heater, whereby the supply of water within the storage tank is replenished. In combination with the parts above mentioned, we employ an additional water heater for providing hot water for purposes other than those for which the water in the storage tank is used, this water being also heated by 60 exhaust steam but preferably by steam from a source different from that of the steam employed in the storage tank and the water heater employed in conjunction therewith. The two water heaters, however, are preferably 65 so combined or connected that if steam is admitted to the second heater in excess of the amount required for heating the water employed therein, this excess steam will pass into the other heater and aid in heating the 70 water passing therethrough to the storage tank.

The preferred embodiment of our invention is illustrated in the accompanying drawing which is a diagrammatic view showing 80 the various devices employed and the connections between them.

Referring to these drawings, 1 indicates the tank in which is stored the water for use in the boilers of the locomotives either as washing water or boiler-feed water; the tank is provided with the usual drain-cock 2. A pump 3 is employed for pumping water from the tank 1 to a suitable main adapted to be connected with the boilers of any of 85 the locomotives in the round house; this pump is connected by a pipe 4 to the upper portion of tank 1 so as to draw the water from the tank at a point near the surface of the water therein and it pumps the water 90 through a pipe 5 to the locomotives. When a locomotive is to be washed and refilled suitable connection is made with a pipe 6 having a check-valve 7 therein and this pipe is connected by a pipe 8 to a blow-off chamber 9. In pipe 8 is a back-pressure valve 10 such that if the pressure within the cham-

ber 9 exceeds a certain pre-determined amount the valve 10 will operate to relieve this pressure. Both the water and the steam in the locomotive boiler are blown off through the pipe 6 to the chamber 9 but it is not desired to employ this blow-off water in heating the water within the tank 1 for the reason that such blow-off water contains impurities which make it unsuitable for further use in a boiler. For this reason a connection is made by a pipe 11 from the upper portion of the blow-off chamber 9 to the storage tank 1 and means are provided for precluding the rising of the water in chamber 9 to such a level as will permit it to flow through pipe 11. Mounted adjacent to or secured to one side of the chamber 9 is a steam trap 12 having therein a suitable float-valve for permitting the escape of the water from the chamber 9 as soon as it rises to a certain level within chamber 9, this water flowing to waste through a pipe 13. Within chamber 9 is a baffle-plate 14 affixed to the wall of the chamber over the opening leading to the steam trap 12 and extending downwardly in proximity to the bottom of the chamber 9 so that the water which flows into the steam trap 12 is drawn from the bottom of the chamber 9. By reason of the provision of this baffle-plate, the water flowing out of the chamber 9 is the colder water at the bottom of the chamber and therefore ample time is secured for the liberation of the steam in the water blown off from the boiler before that water passes out of the blow-off chamber. At the bottom of the chamber 9 is a drain-cock 15. The pipe 11 extends along one or both sides of the storage tank 1 near the bottom of the latter and at a plurality of points along its length is provided with connections 16 for carrying the steam from pipe 11 into the tank 1. Within the tank the steam rises through the water and imparts its heat to the water. From the top of the tank 1, connection is made by a pipe 17 to the upper portion of a feed water heater 18 so that the steam which rises through the water in the storage tank passes through the pipe 17 to the heater 18. Within the heater 18 are a plurality of trays 19 arranged in the usual manner so that water admitted at the top of the heater will pass down through the several trays 19 successively and at the same time the steam carried to the heater 18 by the pipe 17 will pass upwardly through the trays 19 and impart its heat to this water, the steam escaping through an exhaust pipe 20 extending upwardly from the heater 18. Water is admitted to the top of the series of trays 19 by a pipe 21 and this water after being heated by the steam falls within the heater 18 and passes from it through a pipe 22 to the storage tank 1. In order to maintain the proper

level of the water within the supply tank 1 65 by automatically replenishing the supply after water has been drawn from the tank, a float-operated valve 23 is provided in the cold water supply pipe 21, this valve being opened and closed by the float 24 within the 70 tank 1 and connected by suitable levers with the valve 23.

A circulation of water is maintained at all times from the tank 1 through the heater 18 by means of a circulating pump 25 so that 75 the water in the supply tank is being constantly subjected to the heating effect of the steam which has passed through the supply tank 1 and into the heater 18. The circulating pump 25 is connected by a pipe 26 to the 80 top of the heater 18 and it draws water from the bottom of the storage tank 1 through a pipe 27.

In combination with the parts above described a second water heater 28 is employed for heating water for use in devices other than those which are supplied with water from the storage tank 1. The heater 28 receives cold water from the pipe 21 by means of a pipe 29, this water being admitted at the top of the heater and allowed to fall over trays 30. While passing through these trays, the water is subjected to the heating effect of steam admitted to the heater 28 through a pipe 31, this pipe connecting with the exhaust of stationary steam engines and other apparatus which may be employed in the plant. The supply of cold water to the heater through the pipe 29 is controlled by a valve 32 connected in 100 pipe 29 and operated by a float 33 within the heater 28, this float being connected to the valve 32 by suitable levers and links 34, and the water after being heated is drawn off from the bottom of the heater by a pump 105 35 connected to the heater by a pipe 36 as such water is required for use. The two heaters 28 and 18 are preferably built in a single structure but whether they are thus united or built separately a connection is 110 made between them, as shown at 37, so that if the supply of steam through the pipe 31 to the heater 28 is in excess of that required for heating the water admitted to the heater 28, this excess steam will pass 115 through the connection 37 to the heater 18 and in passing up through the trays 19 it will aid in heating the water supplied to the storage tank 1.

The water within the storage tank 1 is 120 normally maintained at or near the temperature desired for water which is to be fed into the boilers of the locomotive for filling the latter in preparing them for use, but in some cases it is desired to use water 125 at a lower temperature than this, as for instance in washing the boilers of the locomotives. To permit of obtaining water at such

reduced temperature a connection is made by a pipe 38 from the cold water supply pipe 21 to the pipe 5 through which water is pumped to the boilers of the locomotives 5 from the storage tank 1. In the pipe 38 is a hand-operated valve 39 and in the pipe 5 is a hand-operated valve 40 so that by regulating these valves water at the desired temperature may be obtained in the pipe 5 beyond the connection of the pipe 38 thereto.

In employing the apparatus above described a locomotive to be washed and refilled is connected in any suitable manner to the pipe 6 and the contents of the boiler 15 of the locomotive are blown off into the chamber 9. Within this chamber the steam rises from the water and the water flows off through the trap 12 and pipe 13 to waste. The water drawn off from the chamber 9 is 20 taken from the bottom of the chamber so that ample time is secured for the liberation of the steam from the water. This steam passes through the pipe 11 to the water in the storage tank so that it serves to 25 heat the water in the tank and such steam as is not condensed in the tank passes through pipe 17 to the heater 18, upwardly through the trays 19 and out through the pipe 20. At all times a circulation is main- 30 tained of water drawn from the bottom of the storage tank 1 through the pipes 27 and 26, over the trays within the heater 18 and then through the connection 22 to the storage tank, so that the stored water is being 35 constantly subjected to the heating effect of the steam within the heater. If any water is drawn from the storage tank the float-valve 23 is automatically operated to admit cold water to the heater 18 which water after 40 being heated is passed into the tank 1 to replenish the supply of the latter. Therefore the tank 1 is kept constantly filled with water at a temperature suitable for introduction into the boilers of locomotives by 45 means of the pump 3 and pipe 5 to refill those boilers, and this water is economically heated by utilizing for this purpose steam blown off from the locomotive. Furthermore, stationary boilers and other apparatus 50 employed in the plant may be supplied with hot water from the heater 28 which water is heated by steam entering the heater through the pipe 31, the level of the water within the heater 28 being automatically 55 maintained by means of the float-operating valve 32 in the cold water supply-pipe 29 of the heater 28. If the steam admitted to the heater 28 is in excess of that required for heating purposes therein, such excess is 60 passed into the heater 18 and utilized there for heating the water supplied to the tank 1.

Water for washing the boilers of locomotives which must be at a lower temperature than that desired for the filling water, is

obtained through the same connection as 65 that by which filling water is supplied by manually operating valves 39 and 40 to admit sufficient cold water from pipe 21 along with the water drawn from the storage tank so that the supply will be at the proper tem- 70 perature.

Having described our invention, what we claim as new therein and desire to secure by Letters Patent of the United States is:

1. The combination of a chamber, a pipe 75 connected thereto adapted for connection to a boiler so that the contents of the boiler may be discharged into said chamber, means for withdrawing the water from the bottom of said chamber, a tank, a pipe connecting 80 the upper part of said chamber with the lower part of said tank for carrying steam from the chamber to the tank, a heater having a water-chamber in the lower portion thereof, a connection between said heater at 85 a point above the water-chamber therein and the upper portion of said tank, a pipe for supplying water to said heater, a valve in said pipe, a float within said tank controlling said valve, a connection between 90 the water chamber within said heater and said tank, a pipe for withdrawing water from said tank, and means independent of said pipe for maintaining a circulation of the water from said tank through said heater, 95 substantially as set forth.

2. The combination of a tank, means for supplying steam to said tank at a plurality of distributed points in the lower portion thereof, an open feed-water heater having 100 a plurality of trays therein and a water-chamber in the lower portion thereof, a water-supply pipe connected to the heater for supplying water to said trays, a valve in said pipe, a float in said tank controlling 105 said valve, a steam connection from the upper portion of said tank to said heater at a point in the heater above the water-chamber thereof, a connection from the water chamber of the heater to the tank, means for 110 withdrawing water from the tank, and means for maintaining a circulation of water from the lower portion of the tank through the heater, substantially as set forth.

3. The combination of a tank, means for 115 supplying steam to said tank at a plurality of distributed points in the lower portion thereof, an open feed-water heater having a plurality of trays therein and a water-chamber in the lower portion thereof, a 120 water-supply pipe connected to the heater for supplying water to said trays, a valve in said pipe, a float in said tank controlling said valve, a steam connection from the upper portion of said tank to said heater at a 125 point in the heater above the water-chamber thereof, a connection from the water chamber of the heater to the tank, means for

withdrawing water from the tank, means for maintaining a circulation of water from the lower portion of the tank through the heater, a second open feed-water heater, a steam supply and a water supply thereto, and a connection between the two heaters for carrying surplus steam in one of the heaters into the other, substantially as set forth.

This specification signed and witnessed to this 12th day of October, 1909.
